CLAIM

The ornamental design for a flash hider, as shown and described.

DESCRIPTION

FIG. 1 is a side elevational view of a flash hider showing my new design;

FIG. 2 is another side elevation view shown in a rotated position thereof;

FIG. 3 is another side elevation view shown in a rotated position thereof;

FIG. 4 is a front view thereof; and,

FIG. 5 is a rear view thereof.

The broken line showing of portions of the flash hider showing in FIG. 4 is included for the purpose of illustrating environment and forms no part of the claimed design.
